UNITED STATES PATENT OFFICE.

FRANCIS A. GOODROW, OF ELGIN, ILLINOIS, ASSIGNOR TO ELGIN NATIONAL WATCH COMPANY, OF ELGIN, ILLINOIS, A CORPORATION OF ILLINOIS.

DESIGN FOR A WATCH-DIAL.

56,425.

Specification for Design.

Patented Oct. 26, 1920.

Application filed March 6, 1920. Serial No. 363,841. Term of patent 14 years.

To all whom it may concern:

Be it known that I, FRANCIS A. GOODROW, citizen of the United States, residing at Elgin, in the county of Kane, State of Illinois, have invented a certain new, original, and ornamental Design for Watch-Dials, of which the following is a description, reference being had to the accompanying drawing, forming a part thereof.

The figure is a plan view of a watch dial, showing my new design.

This design consists in the formation of the face of the dial with the annular outer portion, upon which are placed the Arabic numerals, indicating the hours, this being in yellow metallic letters contrasting with the silvered appearance of the face of the annulus, these numerals being of particular form and large in comparison with the width of the annulus. At the lower portion

there is, having the appearance of an insertion, a seconds disk. In the wide crescent shaped space between the upper periphery of the seconds disk and the inner rim of the outer annulus of the dial, is arranged ornamental scroll work and flower work, as indicated in the drawings, this being illustrated as of white metal contrasting with the yellow background on which it is apparently placed.

I claim:

The ornamental design for a watch dial, as shown.

In testimony whereof, I affix my signature, in the presence of two witnesses.

FRANCIS A. GOODROW.

Witnesses:

ISRAEL HATCH,
EDWARD D. WHEELER.
